Inventor

By his Attorney Louis M. Halsey,
Charles R. Seale

UNITED STATES PATENT OFFICE.

LOUIS M. HALSEY, OF BROOKLYN, NEW YORK, ASSIGNOR TO WALTER M. BRISTOW, OF BROOKLYN, NEW YORK.

AWNING.

1,260,667.

Specification of Letters Patent. Patented Mar. 26, 1918.

Application filed May 28, 1917. Serial No. 171,538.

To all whom it may concern:

Be it known that I, LOUIS M. HALSEY, a citizen of the United States, residing in the city of New York, borough of Brooklyn, in 5 the county of Kings and State of New York, have invented a certain new and useful Improvement in Awnings, of which the following is a specification.

The invention relates to that class of awnings in which the duck or other awning fabric is attached at the lower margin to a bow pivotally connected at its ends to runners arranged to slide on guide-rods in the 10 operation of raising or lowering the awning, and the object of the invention is to provide simple, inexpensive means for automatically engaging the bow-end, runner, and guide-rod and holding these members frictionally in such relation as to prevent movement 15 relatively to each other when the awning is in the lowered and unfolded condition, thus eliminating the annoying rattle due to such movement, and for releasing automatically by the folding movement of the bow in 20 the operation of raising the awning.

The invention consists in certain novel features of construction and arrangement by which the above objects are attained, to be hereinafter described and claimed.

30 The accompanying drawings form a part of this specification and show two approved forms of the invention.

Figure 1 is a side elevation showing a portion of a guide-rod, runner and bow of 35 the usual type, equipped with the invention.

Fig. 2 is a corresponding front view, with the bow-end in transverse vertical section.

Fig. 3 is a corresponding plan view, with the guide-rod in horizontal section.

40 Fig. 4 is a horizontal section partly in plan view.

Fig. 5 is an elevation of one of the bow-sockets.

Fig. 6 is a perspective view of a bridge-plate employed.

Fig. 7 is a plan view showing a modified form of the invention.

Fig. 8 is an end view or rear elevation of the bow-socket employed in such modification.

Similar letters of reference indicate like parts in all the figures.

Referring to Figs. 1 to 6 inclusive, A is one of a pair of guide-rods mounted vertically as usual on the window or door frame 55 and receiving a tubular runner B inclosing the rod and adapted to slide thereon. D is one of the bow-sockets having a tubular extension D¹ adapted to receive the end of the bow C, and has a central opening d receiving 60 an arm B¹ on the runner B and is secured loosely and pivotally thereon by a nut E and washer F or other suitable fastening means.

The main portion D of the bow-socket is circular in form and has an annular rim or 65 flange on the inner face surrounding the opening d, which is shaped to produce two oppositely located cams, and mounted on the arm B¹ between such rim and the runner B is a friction plate G having legs G¹ G¹ 70 bridging the runner vertically and presented adjacent the guide-rod at points above and below the runner.

The spiral cams are so formed and located on the bow-socket D as to ride upon the outer 75 face of the plate G and force the legs G¹ G¹ against the rod A in the act of unfolding the bow C, the reaction being received and resisted by the fastening means E, thus holding all the members at the loose shackle joint 80 under sufficient tension to prevent rattling or any upward movement of the runner on the rod due to the action of the wind on the awning M.

The act of folding the bow preliminary to 85 raising the awning partially rotates the cams in the reverse direction and relaxes the frictional engagement sufficiently to permit the runners to move freely upward on the rods and the awning raised as usual.

90 Each cam may be a simple spiral or incline but is preferably divided into three portions flowing each into the next, comprising a low portion D² which may be plane and of sufficient length to insure relaxation 95 of the grip on the plate G when the bow approaches the end of its upward swing; a spiral portion D³ by which the tension is produced with gradually increasing force when the bow swings downwardly, and 100

gradually relaxed as it is swung upwardly; and a high portion D^4 which may be plane and permits the bow to complete its downward swing and the beginning of its upward swing without relaxing the tension and consequently permits a slight rising and falling swing of the bow without loosening the grip at the joint. The leverage of the bow is greatest in the completely lowered or unfolded condition so that the operation of raising or lowering the awning is performed in the usual manner by manipulating the awning cords, not shown, and without requiring appreciably increased force.

15 The arm B^1 may be cylindrical throughout and the opening g in the plate G may be correspondingly shaped, but in order to prevent displacement by rotation on the arm and to insure the proper presentation of the legs G^1 G^1 to the guide-rod, it is preferable to provide a square or angular portion B^2 on the arm and to square the opening g as shown and thus insure positive engagement. The ends of the legs are notched as at g^1 g^1 20 to aid in maintaining the plate in the desired position relatively to the rod, and by deepening the notches g^1 such position may be satisfactorily maintained without employing the squared portion B^2 of the arm 25 and the correspondingly shaped hole g in the plate.

30

The above described form permits the invention to be applied to the usual awning fixtures with but little change of the latter, 35 mainly the addition of the plate G and its notched legs G^1 . In the modification shown in Figs. 7 and 8 the plate is omitted and the cams, marked D^5 D^6 D^7 coact directly with the surface of the guide-rod A^1 at points 40 above and below the runner B^3 . The action and operation of this simplified form are in all respects similar to those of the form first described.

45 Other modifications may be made in the details of the mechanism, such as the substitution of other fastening means for the nuts E and washers F , and in the forms of the cam surfaces in adapting the invention for various conditions of service.

50 I claim:

1. The combination of a guide-rod and a runner slidably mounted thereon, of a bow-socket rotatably mounted on said runner and adapted to receive an end of an awning bow, said socket having an inclined cam surface thereon arranged to effect an engagement of said rod by the downward swing of said bow in lowering the awning.

60 2. The combination of a guide-rod and a runner slidably mounted thereon, of a bow-socket pivotally mounted on said runner and adapted to receive an end of an awning bow, said socket having oppositely located

inclined cam surfaces thereon arranged to effect an engagement of said rod at points 65 above and below said runner by the downward swing of said bow in lowering the awning.

3. The combination of a guide-rod and a runner slidably mounted thereon, of a bow-socket pivotally mounted on said runner and adapted to receive an end of an awning bow, said socket having a cam surface thereon comprising a substantially plane low portion, and inclined portion, and a substantially plane high portion, said inclined portion arranged to effect an engagement of said rod by the downward swing of said bow in lowering the awning, and said high portion arranged to maintain such engagement uniformly during the completion of such downward movement.

4. The combination of a guide-rod, and a runner slidably mounted thereon, of a bow-socket pivotally mounted on said runner and adapted to receive an end of an awning bow, said socket having an inclined cam surface thereon, and means actuated by said cam surface for engaging said rod by the downward swing of said bow in lowering the awning.

5. The combination of a guide-rod, a runner slidably mounted thereon and having a projecting arm, a bow-socket pivotally mounted on said arm, means for holding said socket on said arm, inclined cam surfaces on said socket adjacent said runner, a plate mounted on said arm between said cam surfaces and said runner and arranged to engage or release said rod by the action of said cam surfaces.

6. The combination of a guide-rod, a runner slidably mounted thereon and having a projecting arm, a bow-socket pivotally mounted on said arm, means for holding said socket on said arm, inclined cam surfaces on said socket adjacent said runner, a plate mounted on said arm between said cam surfaces and runner and having legs adapted to engage said rod above and below said runner by the action of said cam-surfaces upon said plate.

7. The combination of a guide-rod, a runner slidably mounted thereon and having a projecting arm, a bow-socket pivotally mounted on said arm, means for holding said socket on said arm, inclined cam surfaces on said socket adjacent said runner, a plate mounted on said arm between said cam-surfaces and runner and having legs adapted to engage said rod above and below said runner by the action of said cam-surfaces upon said plate, said arm having an angular portion thereon and said plate having a corresponding opening therein receiving and matching to such angular portion.

8. The combination of a guide-rod, a runner slidably mounted thereon and having a projecting arm, a bow-socket pivotally mounted on said arm, means for holding said socket on said arm, inclined cam surfaces on said socket adjacent said runner, a plate mounted on said arm between said cam surfaces and runner and having legs

adapted to engage said rod above and below said runner by the action of said cam- 10 surfaces upon said plate, said legs having each a notch partially inclosing said rod.

In testimony that I claim the invention above set forth I affix my signature.

LOUIS M. HALSEY.
